United States Patent Office

Des. 181,483
Patented Nov. 19, 1957

181,483

PROJECTOR

John R. Miles, Glenview, Ill., assignor to Projection
Optics Co., Inc., Rochester, N. Y., a corporation of
New York

Application March 27, 1957, Serial No. 45,464

Term of patent 14 years

(Cl. D61—1)

Figure 1 is a side view in elevation of a projector embodying my design.

Figure 2 is a front view of the projector shown in Figure 1.

Figure 3 is a rear view of the projector shown in Figure 1.

Figure 4 is a top plan view of the projector shown in Figure 1.

A portion of the drawing figures has been diagonally lined to indicate transparency.

I claim:

The ornamental design for a projector, substantially as shown and described.
